(57) **CLAIM**

The ornamental design for a digital camera, as shown and described.

DESCRIPTION

FIG. 1 is a perspective view of a digital camera showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is top plan view thereof; and,

FIG. 7 is bottom plan view thereof.

Portions in broken lines are for illustrative purpose only and form no part of the claimed design. Dot-dash broken lines define the boundaries of, but not included in, the claimed design.
